INTERLOCKING SYSTEM FOR RAILROADS

Filed July 31, 1931

UNITED STATES PATENT OFFICE

1,969,053

INTERLOCKING SYSTEM FOR RAILROADS

Sedgwick N. Wight, Rochester, N. Y., assignor to
General Railway Signal Company, Rochester,
N. Y.

Application July 31, 1931, Serial No. 554,247

9 Claims. (Cl. 243—3)

This invention relates to interlocking systems, and more particularly to interlocking systems of the free-lever type.

It has been the practice to provide mechanical interlocking between levers, and in many cases electrically locked levers, in interlocking plants for railway systems to afford the necessary protection against setting up conflicting train moves in the railway yard. If electrical or mechanical locking of levers is employed, the levers must of necessity be rather large and the locking mechanism must be comparatively strong, which of course not only makes the lever or control machine cumbersome but also expensive, whereas, on the other hand, free levers may be very small and the entire control machine be made very compact, so that in the smaller plants all levers can be reached by a single man sitting at a desk.

Since a certain amount of time must elapse between the movement of a switch machine lever and the response of the switch machine to such change of lever position, it is considered expedient not to allow the clearing of a signal associated with such switch machine while the switch machine is out of correspondence with its control lever, since otherwise a signal might be cleared for the route present before the switch machine has actually started to move. If, on the other hand, the signal can only be clear with the switch machine lever in correspondence with the switch machine it controls, it would of course be possible to put the signal to stop by moving the switch machine lever, and this is also very undesirable.

In view of the foregoing and other important considerations, it is proposed in accordance with the present invention to employ a "correspondence relay" which can only be picked up if the switch machine lever is in correspondence with the switch machine it controls, and to so organize the circuits that the associated signal cannot be cleared unless the correspondence relay is energized together with means for cancelling the requirement of correspondence of the associated switch machine and its control lever, upon clearing of the signal, so that thereafter movement of the switch machine lever will not put the signal to stop.

Other objects, purposes and characteristic features of the present invention will in part be obvious from the accompanying drawing and will in part be more specifically pointed out hereinafter.

In describing one specific embodiment of the invention in detail reference will be made to the accompanying drawing illustrating one embodiment of the invention.

Referring to the accompanying drawing, the rails 3 of the main track of a railway system have been shown divided into track sections by insulating joints 4, of which the detector track section including the track relay T and the track battery 60 5 only have been shown in detail. From this main track diverges a siding or diverging route having track rails 6 insulated from the detector track circuit by insulating joints 7, through the medium of a track switch S, preferably power operated as by a switch machine SM. At the entrance to this passing siding has been shown a main signal 1 and a diverging route signal 2. Although these signals 1 and 2 have been conventionally illustrated as semaphore signals they 70 65 may be light signals of any suitable construction, well known in the art. As already pointed out the present invention relates principally to the interconnected control of the switch machine and signals 1 and 2, and one particular circuit arrangement for carrying out the control in accordance with this invention will now be specifically described.

The home relay H signifies any suitable relay controlled in accordance with traffic conditions 80 in advance, and as illustrated among other things, is controlled by front contacts 8 and 9 of track relays T and T', respectively. The lock relay L is a relay which is intended to prevent operation of the switch machine SM when it is unsafe to 85 move the switch S, and this relay L is preferably controlled in the following manner. The lock relay L is a stick relay having two pick-up circuits and one stick circuit. The two pick-up circuits for relay L may be traced as follows:—(1) 90 beginning at plus (+), front contact 16 of track relay T, normally open contact 17 of thermal relay TR, wire 18, winding of relay L, wires 19 and 27, contacts 28 and 29 of signals 2 and 1, respectively, closed only when these signals are at stop, to the other terminal (—) and (2) beginning at the terminal (+), back contact 16 of track relay T, wire 18, winding of relay L, wires 19 and 27, and contacts 28 and 29, to the other terminal (—). The stick circuit for this relay L may be 100 traced as follows:—beginning at the terminal (+), front contact 16 of relay T, heating coil 38 of relay TR, stick contact 39 of relay L, wire 18, winding of relay L, wires 19 and 27, contacts 28 and 29 to the other terminal (—). It will be 105 noted that the heating coil 38 is normally included in the energizing stick circuit for the relay L, but the current in this circuit is too small to cause much heating. If one of the signals should be momentarily cleared the relay L would drop, 110

and upon return of the signal to stop the heating coil 38 will be connected directly across the terminals (+) and (-) through the back contact 39 of relay L and after a time, preferably two 5 minutes, will heat the bi-metallic metal of relay TR sufficiently to close contacts 17. It should also be noted that the relay L can be picked up without the lapse of time if the detector track circuit becomes occupied while both signals are 10 at stop, namely through back contact 16 of detector track relay T and wires 18 and 19. These features afford protection against operating the switch machine under dangerous traffic conditions. As conventionally shown, the switch machine SM may be operated to its normal position 15 through the normal wire N when the control relay Z assumes its normal position through the medium of the contact 10 of this control relay Z, providing of course that the lock relay L is energized, as is required by the front contact 11 of 20 the lock relay L and that the detector track section is unoccupied, as required by contact 66 of track relay T. This control relay Z is a polar neutral relay and is controlled from the interlocking office DO, through the medium of snap acting contacts 14 and 15 of a switch machine lever SML, and has included in series therewith one 25 of two windings of an indicating relay IR, all in a manner as more specifically pointed out herein-after.

The relay WP is a switch machine repeater relay, but also serves as a correspondence relay, in that this relay WP will be energized to the position corresponding to that of the switch machine SM only in the event that the switch machine is in correspondence with the control relay Z. This switch machine relay WP is normally energized through the following circuit:—beginning at the terminal (+) of a suitable source of 35 current, contact 20 of the control relay Z, wire 21, switch machine contact 22 closed only when the switch machine SM is in its normal position, wire 23, winding of the relay WP, wire 24, switch machine contact 25, to the other terminal (—) of said source. When the switch machine SM and the control relay Z assumes the reverse dotted position the relay WP will be energized by a current of reverse polarity through a similar circuit 40 readily traced in the drawing and including the wire 26 connecting the contact 20 of relay Z and a contact of the switch machine SM instead of wire 21.

The correspondence relay CR may be picked up only if the switch machine lever SML and the 55 switch machine repeater relay WP assume corresponding positions. The normal pick-up circuit for this correspondence relay CR is shown closed in the drawing and may be traced as follows:—beginning at the terminal (+) of suitable source, contact 30 of the lever SML, wire 31, contact 32 of the relay WP, wires 33 and 34, winding of the correspondence relay CR to the other terminal (—). A similar pick-up circuit for the correspondence relay CR is intact when the switch machine lever SML and the switch machine relay WP assume the dotted position, in which case the wire 35 is included instead of the wire 31, it being apparent that both of these circuits are open when the lever SML is out of correspondence 60 with the relay WP. Attention is directed to the fact that the correspondence relay CR directly controls the signal relays SR¹ and SR², and furthermore that front contacts 36 and 37 of relays SR¹ and SR², respectively, may energize the correspondence relay CR, so that these contacts 65

and 37 really constitute stick contacts for the correspondence relay CR, this because the relays SR¹ or SR² can only be energized after the correspondence relay CR has first been picked up. There are also associated with the lever SML three indicating lamps designated by reference characters signifying a "lock-out indicator" LO, a "transit light" TL and a "correspondence light" CL. In order to more clearly disclose the various features of the present system the operation thereof will be briefly pointed out.

Operation.—As illustrated in the drawing, the switch machine lever SML is in its normal position resulting in the energization of the control relay Z to its normal position through the following circuit:—beginning at the terminal (+) of a suitable battery, contact 15 of the switch machine lever SML, wire 40, lower winding of the indicating relay IR, wire 45, contact 46 of the relay WP, wire 47, front contact 48 of the relay L, wire 49, winding of the control relay Z to the common return wire C connected to the midpoint of said battery. This circuit maintains the control relay Z in its right-hand energized position, thereby closing at one point the normal circuit including the normal wire N for the switch machine SM, heretofore traced, this circuit of course being open within the switch machine through the medium of contacts open only when the switch machine assumes its full normal position.

With the switch machine SM and the control relay Z assuming corresponding positions, the switch machine repeater relay WP will be energized through the circuit heretofore traced to its right-hand normal position.

Let us now assume that it is desired to clear the signal 1 to allow the movement of east-bound traffic on the main track, and that the operator moves his signal lever SL¹ to clear the signal 1. Such movement of the lever SL¹ closes the following circuit for the signal relay SR¹:—beginning at the terminal (+) of a suitable battery, contact of the lever SL¹, wire 50, polar contact 51 of the relay WP assuming its right-hand position, wire 52, front contact 53 of the correspondence relay CR, wire 54, winding of the relay SR¹, to the other terminal (—) of said battery. The closure of this circuit of course effects energization of the signal relay SR¹ and allows clearing of the signal 1 through its contact 64 and clearing wire cl, providing of course that the switch machine SM assumes the main track position as manifested by the closure of contact 55 of the switch machine SM, and providing that the home relay H is energized toward the right as manifested by the closure of its contacts 56 and 59 to the right. When the home relay H is energized to its reverse dotted position the signal 1 or 2, as the case may be is energized to the caution position through its caution wire ca.

Attention is now directed to the fact that the correspondence relay CR is also energized through the following so-called stick circuit:—beginning at the terminal (+) of suitable battery, front contact 36 of the signal relay SR¹, wires 57, 58 and 34, winding of the relay CR, to the other terminal (—). It is apparent that if the operator were to move the switch machine lever SML at a time when the lock relay L is deenergized, as would be the case with the signal 1 clear, that such operation of the switch machine lever SML would not affect the control relay Z, this because the control relay Z is energized under these conditions through the following stick circuit:—beginning at the terminal (+) of a suitable battery,

polar contact 60 of the relay Z, wire 61, neutral contact 62 of the relay Z, wire 63, back contact 48 of the relay L, wire 49, winding of the relay Z, through the common return wire C connected to the mid-point of such battery. Not only would such operation of the switch machine lever SML, under the conditions assumed, not effect operation of the switch machine SM, but furthermore such operation of the lever SML could not effect deenergization of the correspondence relay CR in spite of the fact that contact 30 of lever SML is now out of correspondence with the contact 32 of the relay WP, the correspondence relay CR now being stuck up through the stick circuit heretofore traced including the front contact 36 of the signal relay SR¹. In other words, accidental movement of the switch machine lever SML at a time when the signal 1 is clear, under which condition the switch machine SM is locked against movement, will not effect operation of the signal to the stop position in spite of the fact that the switch machine lever SML is out of correspondence with the switch machine repeater relay WP.

It is apparent that with the lock relay L deenergized, this because the signal 1 has been cleared and has effected deenergization of this lock relay L, such dropping of the lock relay L will effect deenergization of the indicating relay IR, thus closing the back contact 65 of the indicating relay IR and lighting the lock-out lamp LO. Also, movement of the lever SML to the dotted position at this time will result in this lever SML being moved out of correspondence with the relay WP at a time when the indicating relay IR is deenergized and its contact 43 is assuming the retracted position, from which it is apparent that picking up of the lock relay L thereafter will not result in picking up of the indicating relay IR, this because the circuit leading from contact 15 of the lever SML is not connected to a source of energy, it now assuming the dotted position, and the circuit leading from the contact 14 of the lever SML is open at the stick contact 43 of the indicating relay IR, so that even the subsequent energization of the lock relay L will not result in the completion of the control circuit for the relay Z. In other words, movement of the lever SML at a time when the switch machine is locked against movement will not result in the subsequent control of the switch machine or its control relay Z, and the operator will be required to return his lever SML to a position corresponding to that of the switch machine after the lock relay L is again energized in order to again energize the control relay Z, this control relay Z being deenergized its stick circuit opening as soon as the lock relay L picks up.

Let us now assume that the lock relay L is energized and the operator moves the lever SML to the dotted position, under this condition the snap action contacts 14 and 15 of the lever SML very quickly move to their dotted position, they are in fact moved so quickly that the indicating relay IR has not had sufficient time to open its contact 43, so that the indicating relay IR and the control relay Z are now energized in series through the following circuit:—beginning at the terminal (—), contact 14 of the lever SML, wire 67, upper winding of the relay IR, wires 41 and 42, stick contact 43 of the indicating relay IR, wires 44 and 45, contact 46 of the relay WP, wire 47, front contact 48 of the relay L, wire 49, winding of the control relay Z, to the common return wire C connected to the mid-point of said battery. The two windings of the relay IR are so wound

that the flux in the relay structure is in the same direction for the two circuits, this prevents opening of the contact 48 during shifting from one circuit to the other of this relay. The completion of this circuit operates the control relay Z to its left-hand position, thereby energizing the switch machine SM through the reverse circuit including the reverse wire R, and upon completion of its stroke results in operation of the relay WP to its dotted position, so that the stick contact 43 is no longer included in the energizing circuit for the control relay Z.

It is of course understood that as soon as the control relay Z has been operated to its dotted position the energizing circuit for the switch machine repeater relay WP is broken at the contact 10 of the relay Z, thereby effecting dropping of the neutral contact 70 of the relay WP and illumination of the transit light TL, this transit light TL being extinguished as soon as the switch machine SM has been operated in correspondence with the control relay Z. Also, since the signal levers SL¹ and SL² were assumed to be in their normal stop position when the switch machine SM was in its reverse position, the correspondence relay CR was deenergized during the interim of operation of the switch machine lever SML and its contact 30 and the operation of the contact 32 of the relay WP, so that the correspondence relay CR illuminated the out-of-correspondence light CL during this period, through the medium of the contact 71 of the relay CR.

In the same manner as already explained in connection with the signal relay SR¹, the signal relay SR² cannot be energized unless the contact 72 of the switch machine repeater relay WP assumes its take-siding dotted position, the signal lever SL² assumes its clear position and the correspondence relay CR assumes its energized position as manifested by the contact 73 of the relay CR, and that with the signal relay SR² once energized the correspondence relay CR is then stuck up through the front contact 37 of the relay SR².

Applicant has thus provided a system in which the switch machine cannot be operated unless the switch machine control lever SML is operated at a time when the switch is unlocked, namely when the lock relay L is energized, that a signal cannot be cleared unless the switch machine lever is in correspondence with the switch machine, and that with a signal once clear the placing of the switch machine lever out of correspondence with the switch machine will not result in the movement of a signal to the stop position, this because correspondence of the switch machine with its control lever is only necessary during the process of clearing the signal and is not necessary after the signal has once been cleared.

Having thus shown and described one rather specific embodiment of the present invention, it is desired to be understood that the particular circuit arrangement illustrated has been selected as an exemplification of the invention and has not been selected for the purpose of showing the scope of the invention nor the exact construction preferably employed in practicing the invention, but has been selected to facilitate describing the underlying principles of the invention, its mode of operation and the novel functions accomplished thereby, and that various changes, modifications and additions may be made to adapt the invention to the particular problem encountered in practicing the same, all without departing from the spirit or scope of the invention except as demanded by the scope of the following claims.

It is further desired to be understood that the applicant is acquainted with the subject matter of the pending application of R. M. Phinney, Ser. No. 539,486 filed May 23, 1931, and the pending application of G. J. Johaneck, Ser. No. 533,899 filed April 30, 1931, that the applicant positively disclaims any right to the subject matter contained in such applications, and that the applicant claims a right to only those features of the present invention which are improvements over the disclosures of the above named applications.

What I claim as new is:—

1. In a system for electrically interlocking railway traffic controlling devices, a track switch operated by a switch machine, signals governing traffic over said track switch, a control relay for controlling said switch machine, a lever for controlling said control relay, contacts operated by said switch machine, a switch repeater relay arranged to indicate the correspondence of the position of said contacts with the position of said switch machine control relay, a correspondence relay initially energized only when said switch repeater relay and said control lever for controlling said control relay assume corresponding positions, signal control relays having energizing circuits including contacts on said switch repeater relay and contacts on said correspondence relay, and a circuit organization for said correspondence relay including a front contact on each of said signal control relays in multiple, whereby the control of said signals is subject to the correspondence of said switch control lever and said switch repeater relay only when said signal control relays are deenergized. 80
2. In a system for electrically interlocking railway traffic controlling devices, a track switch operated by a switch machine, signals governing traffic over said track switch, a control circuit for said switch machine including contacts of a control lever, lockout means for preventing the control of said switch machine through said control circuit, a correspondence relay energized in accordance with the correspondence of said switch machine and its control lever, control relays for said signals, energizing circuits for said signal control relays including contacts of said correspondence relay, and a second energizing circuit for said correspondence relay including a contact of one of said signal control relays. 85
3. In a system for electrically interlocking railway traffic controlling devices, a track switch operated by a switch machine, signals governing traffic over said track switch, a control relay for said switch machine, a manually operable lever controlling said switch machine control relay, lockout means for preventing the control of said switch machine control relay, a switch repeater relay arranged to check the correspondence of said switch machine and said switch machine control relay, a correspondence relay arranged to check the correspondence of said switch repeater relay and said switch control lever, signal control relays for said signals having energizing circuits which include contacts on said switch repeater relay and contacts on said correspondence relay, and a stick circuit for said correspondence relay including contacts of one of said signal control relays. 90
4. In combination, a railway system including a track switch, a switch machine for operating said track switch, a lever for controlling said switch machine, a lock-out relay for when de-energized preventing control of said switch machine in response to a change in the position of said lever, a correspondence relay initially energizable only when said lever and said switch machine assume corresponding positions, a signal for governing traffic over said track switch which signal must be at stop to energize said lock-out relay, a signal device which must be energized to cause said signal to display a proceed indication, a circuit for energizing said signal device including a front contact of said correspondence relay, and a second circuit for said correspondence relay including a contact of said signal device closed only when said signal device is energized, whereby correspondence between said lever and switch machine is necessary only during the act of clearing of said signal. 95
5. In combination, a track switch, a switch machine for operating said track switch, a control lever having a snap-action contact for controlling said switch machine, a signal for governing movement of traffic over said track switch, a clearing circuit for said signal which may be closed only if said track switch and said control lever assume corresponding positions but which if closed will remain closed independently of correspondence of said switch machine and said control lever, and means for indicating when said switch machine assumes an extreme position but out of correspondence with said control lever. 100
6. In combination, a track switch (S), a switch machine (SM) for operating said track switch (S), a lever (SML) for governing the operation of said switch machine (SM), a switch position repeating relay (WP), a correspondence relay (CR), a pick-up circuit (33) for said correspondence relay closed only when said lever (SML) 105 and said switch position repeating relay (WP) assume corresponding positions, a signal (1) governing traffic over said track switch (S), a signal control relay (SR¹) for said signal, circuit means for clearing said signal (1) when its control relay (SR¹) is energized, manually operated means (SL¹) for energizing said control relay (SR¹) only when said correspondence relay (CR) is energized, and a circuit (58) for said correspondence relay (CR) including a contact (36) of said 110 signal control relay (SR¹). 115
7. In combination, a track switch, a switch machine for operating said track switch, a lever for governing the operation of said track switch, a switch position repeating relay, a correspondence relay closed only when said lever and said switch position repeating relay assume corresponding positions, a plurality of signals governing traffic over said track switch, a signal control relay for each of said signals, control circuits for each of said signals including a front contact of its corresponding signal control relay, an energizing circuit for each of said signal control relays including a front contact of said correspondence relay, and a holding circuit for said correspondence relay including a front contact of any one of said signal control relays. 120
8. In combination, a track switch, a switch machine for operating said track switch, a lever for governing the operation of said switch machine, a switch position repeating relay, a correspondence relay, a pick-up circuit for said correspondence relay closed only when said lever and said switch position repeating relay assume corresponding positions, a plurality of signals governing traffic over said track switch, a signal control relay for each of said signals, control circuits for each of said signals including a front contact of its corresponding signal control relay, 125
9. In combination, a track switch, a switch machine for operating said track switch, a lever for governing the operation of said switch machine, a switch position repeating relay, a correspondence relay, a pick-up circuit for said correspondence relay closed only when said lever and said switch position repeating relay assume corresponding positions, a plurality of signals governing traffic over said track switch, a signal control relay for each of said signals, control circuits for each of said signals including a front contact of its corresponding signal control relay, 130
10. In combination, a track switch, a switch machine for operating said track switch, a lever for governing the operation of said switch machine, a switch position repeating relay, a correspondence relay, a pick-up circuit for said correspondence relay closed only when said lever and said switch position repeating relay assume corresponding positions, a plurality of signals governing traffic over said track switch, a signal control relay for each of said signals, control circuits for each of said signals including a front contact of its corresponding signal control relay, 135
11. In combination, a track switch, a switch machine for operating said track switch, a lever for governing the operation of said switch machine, a switch position repeating relay, a correspondence relay, a pick-up circuit for said correspondence relay closed only when said lever and said switch position repeating relay assume corresponding positions, a plurality of signals governing traffic over said track switch, a signal control relay for each of said signals, control circuits for each of said signals including a front contact of its corresponding signal control relay, 140
12. In combination, a track switch, a switch machine for operating said track switch, a lever for governing the operation of said switch machine, a switch position repeating relay, a correspondence relay, a pick-up circuit for said correspondence relay closed only when said lever and said switch position repeating relay assume corresponding positions, a plurality of signals governing traffic over said track switch, a signal control relay for each of said signals, control circuits for each of said signals including a front contact of its corresponding signal control relay, 145
13. In combination, a track switch, a switch machine for operating said track switch, a lever for governing the operation of said switch machine, a switch position repeating relay, a correspondence relay, a pick-up circuit for said correspondence relay closed only when said lever and said switch position repeating relay assume corresponding positions, a plurality of signals governing traffic over said track switch, a signal control relay for each of said signals, control circuits for each of said signals including a front contact of its corresponding signal control relay, 150

an energizing circuit for each of said signal control relays including a front contact of said correspondence relay, a holding circuit for said correspondence relay including a front contact 5 of any one of said signal control relays, and means for automatically opening said energizing circuit for that signal which is cleared upon the passage of a train to thereby put that signal to stop independently of its corresponding signal 10 control relay, whereby the passage of the train does not open the holding circuit of said correspondence relay.

9. In combination, a control lever for governing a power operated track switch, a switch position repeating relay governed in accordance 15 with the power operated track switch, a correspondence relay, a pick-up circuit for said correspondence relay closed only when said control lever and said switch position repeating relay

20

are in corresponding positions, signals for governing traffic over said track switch, manually controlled means for clearing said signals, stick circuit means for maintaining said correspondence relay energized independently of the correspondence between said control lever and said switch position repeating relay whenever said manually controlled means is in condition to clear any of said signals, means for causing any clear signal to automatically assume a stop condition upon the passage of a train independently of said manually controlled means and without rendering said stick circuit means ineffective, whereby such signal being automatically put to stop will automatically clear when the train has passed if its corresponding manually controlled means is still in a clearing condition.
